UNITED STATES PATENT OFFICE.

NICHOLAS HAYDEN AND CHARLES FREDERICK CLINTON WURST, OF
ST. PAUL, MINNESOTA.

DESIGN FOR A CALENDAR-CASING.

SPECIFICATION forming part of Design No. 29,137, dated August 2, 1898.

Application filed July 21, 1897. Serial No. 645,473. Term of patent 14 years.

To all whom it may concern:

Be it known that we, NICHOLAS HAYDEN and CHARLES FREDERICK CLINTON WURST, citizens of the United States, residing at St. 5 Paul, in the county of Ramsey and State of Minnesota, have invented and produced a new and original Design for Calendar-Casings, of which the following is a specification, reference being had to the accompanying 10 drawing, showing the same in perspective.

This invention relates to a new and original design for calendar-casings, the said design contemplating an arrangement which presents a very artistic effect, the principal 15 features of which are a foreground represented by two large rocks, a spread-eagle standing upon the rocks, with an American flag and staff in its beak, and a similar flag and staff in the claws of one foot, the back- 20 ground being taken up by snow-capped mountain-peaks and a waterway with sailing vessels thereon.

In the accompanying drawing of my design there is illustrated the rocky bed, forming 25 the foreground, with a spread-eagle standing thereon, and flags upon the poles or staffs,

one being carried in the beak and the other held by one of his feet. In the background, upon the right, is a scene of a range of snow-capped peaks, while on the left is represented 30 a body of water with sailing vessels thereon, the sky being studded with clouds. Inclosing the picture just described is a ring having a series of blank spaces thereon. In connection with this ring is a second ring con- 35 centric therewith.

The description, in connection with the accompanying drawing, fully illustrates the design, and it will appear that the general arrangement of the features is such as to present a very pleasing and artistic effect. 40

Having thus described the invention, what we claim as new and original is—

The design for a calendar-casing, substantially as shown and described. 45

In testimony whereof we affix our signatures in the presence of two witnesses.

NICHOLAS HAYDEN.

CHARLES FREDERICK CLINTON WURST.
